ATTORNEY.

UNITED STATES PATENT OFFICE.

HARRY A. SHEETZ, JR., OF NEW YORK, N. Y.

VULCANIZER.

1,396,069.

Specification of Letters Patent. Patented Nov. 8, 1921.

Application filed November 16, 1920. Serial No. 424,345.

To all whom it may concern:

Be it known that I, HARRY A. SHEETZ, Jr., a citizen of the United States, residing at New York, in the county of Bronx and State of New York, have invented certain new and useful Improvements in Vulcanizers, of which the following is a specification.

This invention relates to vulcanizers, and especially to the small portable vulcanizer which carries a vulcanizing patch upon a metal receptacle: the receptacle carrying a fuel element composed of card board, or other suitable material, impregnated with salt peter or similar combustible.

An object of this invention is to provide upon the receptacle, a means for igniting a match, or other igniter, and to so protect the flame from draft and bring it into such relation with the fuel element, that the fuel element may be quickly ignited under conditions where ignition would be difficult.

With these and other objects in view, the invention consists in the construction, combination, detail, and an arrangement of parts as hereinafter more fully described and claimed.

In the drawings:

Figure 1 is a plan view of my device.

Fig. 2 is a section of 2—2 of Fig. 1.

Fig. 3 is a fragmentary section of the bottom of the receptacle showing the roughened surface area.

Fig. 4 is a fragmentary plan view of a modified form.

Fig. 5 is a fragmentary view of the bottom of the receptacle shown in Fig. 3 showing the modified form of roughened area.

Fig. 6 is a fragmentary plan view of another modification.

Fig. 7 is an end section of Fig. 6.

Fig. 8 is a fragmentary plan view of another modified form.

Fig. 9 is an end section of Fig. 8.

Fig. 10 is a fragmentary plan view of another modified form.

Fig. 11 is a section of 11—11 of Fig. 10.

Fig. 12 is a detail in plan of the fuel element showing the cut away portion.

In the embodiment of my invention there is provided a pair of fuel elements 2 and 3, consisting of card board impregnated with salt peter, or other combustible element,

mounted in the receptacle 4, which receptacle is provided at 5 with a roughened surface. The fuel elements 2 and 3 are cut off as in a chord at 6, thereby leaving a space between the fuel elements and the sides of the container for the insertion of a match or other igniting means whereby the abrasion of the match upon the roughened surface 5 will cause the match to ignite and light the fuel element; the flame being protected by the sides formed by the fuel elements and the sides of the container forming.

In the modified form shown in Fig. 4, I provide roughened lines instead of dotted area shown in Fig. 1. In the modified form in Fig. 7, I provide a means of striking the match on the inner surface of the box or receptacle, providing a plurality of dots; while in the modified form shown in Fig. 8, I provide a lined roughened surface on the inner surface in a similar place to that shown in Fig. 7. In the modified form shown in Fig. 10, I insert in the corner of the box or receptacle, which may be either fixed to the box or receptacle, or to the bottom of the fuel element, or may be left loose in the bottom of the box and held by the box or otherwise, a piece of sand paper which provides a roughened surface similar to that shown in Figs. 1 and 4.

What is claimed is:

1. In a vulcanizer, the combination of a fuel element and a receptacle for said fuel element, a roughened surface on the interior of said receptacle, the said fuel element removed to provide a pocket and passageway for a match to be abraded upon said roughened surface.

2. A vulcanizer comprising a fuel element, a receptacle for said fuel element, and a vulcanizing patch upon the bottom of said receptacle, the said fuel element containing impregnated card board, a roughened spot on the bottom of said receptacle, the said card board cut away over said roughened spot.

3. In a vulcanizer, a fuel element comprising an impregnated card board, a pan receptacle for retaining said card board, said receptacle provided on its bottom with a vulcanizing patch, the said receptacle impressed upward to form a roughened sur-

face and the said card board cut away over the said roughened surface.

4. In a vulcanizer igniter, the combination of a pan receptacle carrying a fuel element with a vulcanizing patch on the bottom of said receptacle and a roughened surface on said receptacle for striking a match
- 5

thereon, and an open space on said fuel element for the insertion of said match, said open space being adjacent to said roughened surface.

In testimony whereof I affix my signature.

HARRY A. SHEETZ, JR.
